UNITED STATES PATENT OFFICE.

COLUMBUS MILLER, JOHN W. BLUE, AND CHARLES S. MILLER, OF KEYSTONE,
MISSOURI.

CHURN.

SPECIFICATION forming part of Letters Patent No. 429,356, dated June 3, 1890.

Application filed March 14, 1890. Serial No. 343,936. (No model.)

To all whom it may concern

Be it known that we, COLUMBUS MILLER, JOHN W. BLUE, and CHARLES S. MILLER, of Keystone, in the county of Clinton and State 5 of Missouri, have invented a new and useful Improvement in Churns, of which the following is a specification.

This invention is an improvement in churns; and it consists in certain novel constructions 10 and combinations of parts, as will be herein-after described and claimed.

In the drawings, Figure 1 is a vertical longitudinal section of the churn. Fig. 2 is a cross-section thereof on about line 22 of Fig. 15. Fig. 3 is a detail perspective view of the dasher and shaft and its supporting and operating devices, and Fig. 4 shows the single dasher.

The churn-body has a suitable lid *a*, and is 20 provided in its ends with bearings *B* and *C*. The dasher-shaft *D* has the dasher-section *H'* secured to its central portion, and is formed near its ends at *h'* to provide journals for the end tubes or portions *i'* of the 25 dasher-section *I*. This section *I* is made in the form of a frame journaled at *h'* on the shaft *D*. The section *H'* operates within the section *I*, with its blades *h* operating between the inwardly-projecting blades *i* of the 30 section *I*.

It will be seen from the foregoing that the dasher-sections *H'* *I* may be turned in opposite directions, the tube or sleeve-like portions *i'* turning freely on the parts *h'* of the 35 shaft *D*. At one end the shaft *D* is formed to receive the point of screw *E*, which is threaded in bearing *B*, while at its opposite end the shaft has a square or angular stem or tenon *D'*. This stem *D'* is received in an 40 angular socket *f* in the inner end of a sub-shaft *F*, which extends at its outer end beyond the side of the casing, and is provided at such end with a pulley *F'*. A shaft *G*, in the form of a sleeve, journals in bearing *C* and 45 encircles the shaft *F*, so as to turn freely thereon and to permit the free independent turning of such section *F*. This shaft *G* is flared or enlarged at its inner end, and is adapted at such end to engage the dasher- 50 section *I*, being preferably provided with ap-

proximately diametrically-opposite notches *g* *g*, which receive the edge of section *I*, so such section will be turned by the turning of shaft *G*. At its outer end the shaft *G* is provided with a gear-wheel *G'*.

55

In operation the wheels *F' G'* and their attached shafts and operated parts are turned in opposite directions, preferably by means of pulley-wheel *F²* and gear-wheels *G²*, a belt *F²* or sprocket-chain connecting wheels *F' F²*, and the wheels *G' G²* being arranged to mesh, such wheels *F² G²* being fixed so they will turn together, preferably by securing them on a common shaft, as shown.

By the described construction it will be 65 seen that the turning of shafts *F* and *G* will operate to turn the dasher-shafts in opposite directions, such sections being so constructed as to break up every particle of the milk and cream when so operated.

70

While we much prefer the double dasher *H' I*, as shown, it will be understood that where a single dasher is desired the single dasher shown in Fig. 4 may be used.

Manifestly, where the shafts *D F* connect, 75 it would involve no departure from the invention to reverse the socket-and-stem formation—that is to say, to make the socket in section *D* and the stem or tenon on the section *F*, as such construction would be in a 80 measure the equivalent of that shown.

It will be understood that the pulley *F'* and gear *G'* are connected with the dasher-sections, so that the said dasher-sections may be regarded as provided with such wheels. 85

The churn-body is provided below its churning-chamber with a water-receiving chamber *N*, formed between the bottom plate of the churn-body and the false bottom *n*, such chamber extending up along the sides of and 90 from end to end of the body, and having at one side an opening *N'*, through which the water may be supplied.

Having thus described our invention, what we claim as new is—

95

1. In a churn, the combination of the inner dasher-section *H'*, the shaft *D*, secured to and supporting section *H'* and extended at its ends beyond said section, forming journal portions for the outer dasher *I*, the dasher-

100

section I, fitted over the section H' and having at its ends portions i', fitting and turning on the journals at the ends of shaft D, whereby such shaft supports the inner dasher-section 5 and forms bearings for both ends of the outer dasher-section, the shafts F and G, engaging said shaft and dasher-section I, and operating means whereby such shafts may be turned in opposite directions, substantially as 10 and for the purposes set forth.

2. In a churn, the combination of the dasher-section H', having shaft D, provided with tenon D', the dasher-section I, fitted over the section H' and journaled on shaft D, the 15 shaft F, having at its inner end a socket receiving the tenon D', the shaft G, fitted over the shaft F and having at its inner end notches g to receive the end of dasher I, means for operating such shafts F and G, and means 20 for supporting the other end of the dasher, all substantially as and for the purposes set forth.

3. In a churn, the combination of the shaft D, having at its ends bearings h', the dasher-section H', secured to such shaft D, the dasher-section I, fitted over the section H' and having at its ends tube or sleeve-like portions i',

journaled on bearings h', the shaft F, connected at its inner end with the shaft D, the shaft G, having its inner end notched to engage the dasher-section I, and the drive-gearing, all substantially as and for the purposes 30 set forth.

4. In a churn, the combination, substantially as hereinbefore described, of the shaft 35 D, having at its ends bearings h' h', the dasher-section H', secured to such shaft D between bearings h', the dasher-section I, having at its ends tube or sleeve-like bearings journaled on bearings h', the screw by which 40 to support one end of shaft D, the shaft F, having at its inner end a non-circular socket receiving a non-circular tenon on the shaft D, the shaft G, encircling shaft F and having at its inner end notches to receive the edge of 45 dasher-section I, and mechanism by which to turn such shafts F and G in opposite direction, substantially as described.

COLUMBUS MILLER.
